UNITED STATES PATENT OFFICE

2,150,104

APPARATUS FOR MAKING BOOK COVERS

Winfred Elmo Reavis, Los Angeles, Calif., assignor to Picture Cover Bindings, Inc., Brooklyn, N. Y., a corporation of New York

Original application May 25, 1936, Serial No. 81,669. Divided and this application October 10, 1936, Serial No. 105,027

10 Claims. (Cl. 11—2)

My invention relates to the art of book binding and relates in particular to an apparatus for covering books and which is of especial utility in the practice of recovering books, wherein the 5 covers or cases are fabricated completely before the book bodies are fastened therein. The present application is a division of my copending application, Serial No. 81,669, filed May 25, 1936, entitled "Method and means for recovering books."

Book covers of the type referred to herein ordinarily consist of a covering sheet of a suitable material, such, for example, as fabric, which in its use upon the book is divided into three principal sections or areas, namely, a back area and front and rear areas which lie upon opposite sides of the back area. Ordinarily there are narrow areas between the front, back, and rear areas coinciding with the joints of the cover. The front 15 and rear areas are ordinarily reinforced by pieces of binder's board or heavy cardboard, but in some instances the front and rear areas are reinforced with a flexible material, such as thin cardboard, so that the bound book will be flexible in character.

It is an object of my present invention to provide an apparatus whereby book covers may be completely fabricated before being placed upon the book bodies, in which the covers may be made 20 from cover sheets which are already decorated or lettered, or both, and in which a practically perfect alignment of the markings of the cover sheets may be maintained relative to the completed covers.

The use of pre-marked covering material, or 25 cover sheets, necessitates particular care in the location of the other elements entering into the construction of the covers, namely, the pair of binder's boards entering into the front and rear of the cover, and an inlay strip of paper forming the reinforcement for the back portion of the cover, so that when the case is completed, the markings will be located desirably or as intended 30 relative to the covered or recovered book.

It is an object of my invention to provide an apparatus whereby the required markings of the cover sheet are located or positioned with direct 35 relation to two adjacent edges, referred to as the guide edges, of the cover sheet, and wherein the front, rear, and back area reinforcing members, or liners, are glued to the reverse side of the cover sheet in a definite or corresponding relation to the same guide edges of the material, thereby assuring that when the cover is completed and applied to a book body, the markings thereof will be properly aligned and positioned 40 relative to the externally exposed areas of the recovered book.

It is a further object of the invention to provide 45 a cover sheet prepared by a part of my appara-

tus for use in another part of my apparatus, this cover sheet contributing to the accomplishment of the improved results which I obtain.

Further objects and advantages of the invention will be made evident throughout the following part of the specification.

Referring to the drawings, which are for illustrative purposes only,

Fig. 1 is a perspective view of a book body which is to be covered or recovered. 10

Fig. 2 is a perspective view of the book body with a cover applied thereto.

Fig. 3 is a face view of a decorated and lettered cover sheet.

Fig. 4 is a face view of a decorated cover sheet. 15

Fig. 5 is a face view of a cover sheet marking device.

Fig. 6 is a fragmentary section on a plane represented by the line 6—6 of Fig. 5.

Fig. 7 is a rear face view of the cover sheet 20 shown in Fig. 3, with the cooperating physical elements in place thereon.

Fig. 8 is a face view of a simple device for positioning the physical elements of a book cover in accordance with known information relative 25 to the book body which is to be covered.

Fig. 9 is a partly sectioned elevational view looking toward Fig. 8 as indicated by the arrow 9 thereof.

Fig. 10 is a section taken as indicated by the 30 line 10—10 of Fig. 8.

Fig. 11 is a fragmentary section on a plane represented by the line 11—11 of Fig. 8.

Fig. 12 is a plan view of an alternative form of liner locating device by which the invention may 35 be practiced.

In Fig. 1 I show a book 20 which, for the reason that it does not have a cover applied thereto, I shall hereinafter refer to as the book body so that when this book body 20 is covered, it may 40 be referred to as the completed book or merely "book." My present invention is particularly useful in covering book bodies, either new or old, but since it has its principal utility in connection with the recovering or rebinding of books, I shall 45 hereinafter explain the invention with particular reference to this use thereof. When a book is brought in for rebinding, the old cover is stripped from the book body which may be then trimmed so that the edges of all of the leaves 50 will be even. Subsequently, the back of the book body may be glued so that the leaves thereof will be held in a stack. This is ordinarily followed by separating the book body into a plurality of relatively thin tablets each having a 55 glued back, and the tablets are then sewed together by use of a resewing machine. After resewing, the book body 20 is generally placed in a clamp so that its back 21 projects slightly from the edges of the clamp, whereupon the back is 60

spread as indicated at 22 so that the back 21 has a dimension b which is a little greater than the thickness t of the book body 20.

In Fig. 2 I show a book cover 23 applied to the book body 20. In view of the fact that the width w , height h , and back b dimensions are obtainable by reference to the book body 20, the similar dimensions W, H, and B of the book cover 23 may be readily determined so that when the cover 23 is applied to the book body 20, there will be top and bottom projections and a front projection of the book cover from the book body 20, as indicated at 24 and 25 in Fig. 2. The cover 23 includes a front member 26 and a rear member 27, which are spaced from a back 28 by joints 29 having a dimension j . In Fig. 7 I show a cover sheet 31 lying flat with its inner, inside, or rear face up and with a front board 32 and a rear board 33 lying on opposite sides of a back filler strip 34 and being spaced from such back filler strip 34 by a joint dimension J which is determined in accordance with the thickness of boards and flexibility of joint desired. Ordinarily, this joint dimension J is approximately $\frac{1}{4}$ ". The cover sheet 31 is of such dimension that upper and lower fold-in edges or extensions 35 and 36 will be provided, and also side fold-in extensions 37 and 38 will be provided, the width of such edges 35, 36, 37, and 38 being determined with relation to the thickness of the boards 32 and 33 and the amount of lap desired. From the foregoing it will be perceived that a cover sheet 31 for any size of book body may be predetermined, and likewise that various standard sizes of such cover sheets may be pre-cut and held in stock ready for use as required.

It occurs that in the libraries of a city or district, there may be a relatively large number of copies of a popular book, and at the end of a period of time a large number of the copies of this one book may require rebinding. My invention makes it possible to economically prepare a supply of cover sheets for use in the recovering of this particular book, which cover sheets may be held in stock by a rebinding establishment and used for the recovering of the copies of the book as they come in to the bindery for attention. Likewise, a supply of cover sheets for the recovering of this book may be held in a central warehouse from which they may be sent to various binderies throughout the country as need thereof is required. The covers thus used in the recovering of copies of this book may be decorated and printed more elaborately than the ordinary cover used in the recovering of library books, and in fact may be a replica of the original cover of the book without incurring material additional expense to the library or libraries for whom the recovering work is done.

An example of a preferred practice of my invention is as follows: Let it be assumed that the book body 20 shown in Fig. 1 is from a popular book of which there are numerous copies held in libraries, many of which copies are in such condition that they require or will eventually require recovering. From the physical dimensions of the book body 20, as previously described, the size of a cover sheet 31 may be readily determined, and an estimated number of such cover sheets may be cut. As one of the steps of the process which may be conveniently first performed, this group of cover sheets is provided with means for establishing a reference line which may be hereinafter referred to as the back reference line, X—X shown in Figs. 3, 4, and 5. As clearly

shown in Figs. 3, 4, and 7, the indication for determining the position of this back reference line X—X is preferably made by the removal of a small amount of material from the cover sheet to form an incisure and may be in the form of a small notch 40 cut in the top or front edge 41 of the cover sheet 31 as shown in Fig. 3. This notch 40, and likewise the reference line X—X defined thereby, is a predetermined distance from a side edge 42 of the cover sheet 31, and the purpose of the back reference line X—X is to provide the binder with information from which he may determine the position of the back of the cover which is to be formed from the cover sheet 31.

In a preferred practice of the invention the notch 40 is placed at a distance R from the edge 42, such distance R as shown in Fig. 7 being the sum of the dimensions L, W, and J. The reference line X—X determined thereby accordingly indicates the position of the edge 43 of the filler or back liner 34.

In Fig. 5 I show my marking device 45 by which cover sheets are provided with indications such as notches 40 for defining the position of the back reference line X—X. Such device comprises a board or table 46 having a head guide 47 and a side guide 48 which projects from a laterally sliding head 49 adapted to make threaded engagement with a screw 51 so that by rotation 30 of such screw 51 through use of a knob 52 provided thereon, the side guide 48 may be moved relative to a notching cutter 53. This notching cutter 53 is mounted on a vertically movable head 54 formed in conjunction with a bar 55 carried in vertical slides 56 and having pivot means 57 at its upper end engaging an operating lever 58. By means of a pin 59, the rearward end 61 of the operating lever 58 is pivotally connected to bars or links 62, the lower ends of which are pivotally connected by means of a pin 63 to a bracket 64 mounted on the upper edge of the board or table 46.

After the cutting of the cover sheets 31, the side guide or stop 48 may, by reference to a scale 65, be set at a distance R from the center or point of the notching cutter 53, after which a stack 66 of the cover sheets 31 may be placed so that the front edges 41 of these cover sheets will rest against the head guide 47, as shown in Figs. 5 and 6, and so that the side edges 42 will rest against the side guide 48. The lever 58 may be operated to move the cutter 53 downwardly from the position in which it is shown in Fig. 6, thereby cutting indicating notches 40 in the edges of the cover sheets 31.

The cover sheets 31 are then imprinted or otherwise provided with markings on the front faces thereof, as indicated by the numeral 67 of Fig. 3. It is well known that regardless of the care which may be taken in the cutting of the cover sheets 31, they may vary more or less in dimension, and the edges thereof may not be perpendicular one to the other. For example, as indicated by the dotted line 68 of Fig. 3, a cover sheet may be slightly longer than the estimated proper dimension thereof; and as indicated by the dotted line 69, such cover sheet may be at the same time slightly less in width than the specified width dimension. Accordingly, I establish two guide edges, namely, the front edge 41 and the side edge 42 as guide edges with reference to which all of the operations on the cover sheets 31, in the preparation of such cover sheets and in the making up of the covers, are per-

formed. As previously described herein, the reference line X—X is established a specified distance R from the side guide edge 42. Likewise, all of the printing or decorating of the cover sheet 31 is applied with reference to or in spaced relation to the guide edges 41 and 42. The markings 67 on the cover sheet 31 may be of several different colors consecutively applied, and in the application of such colors the edges 41 and 42 are placed in engagement with or in a definite relation to guide means provided therefor in the imprinting or decorating apparatus. By following this procedure, I assure that the various parts of the markings 67 will not only be in register, but that they will also be positioned on the cover sheet 31 so that when the book cover is completed, the markings will be properly aligned and properly positioned relative to the cover and will not be diagonally misaligned or offset from the intended position thereof on the finished book cover.

The markings 67 include decoration 71, lettering of identification 72, and also lettering 73 properly positioned in that area of the cover sheet which is to form the back of the completed cover. When the cover is to be made up, a back liner 34 is selected having a width dimension b corresponding to the back 21 of the book body 20. This liner 34 indicated in Fig. 7 is secured to the inner face 74 of the cover sheet 31 in a definite position relative to the back reference line X—X or to the back reference indication formed by the notch 40. The boards 32 and 33, which may also be referred to as liners, are then placed on opposite sides of the back liner 34 in spaced relation thereto, with the result that they are in a definitely spaced relation to the guide edges 41 and 42, in view of the fact that the reference line X—X has been located in predetermined spaced relation to the side guide edge 42. I prefer to place the liners 32 and 33 on the rear face of the cover sheet 31 in spaced relation to the back liner 34 for the reason that any variation in dimension of these liners 32 and 33, as indicated in dotted lines 75 in Fig. 7, will be compensated for in those edges 76 and 77 of the liners 32 and 33 lying distant from the back reference line X—X and the guide edge 41.

For use with the cover sheets 31 I employ an aligning and positioning device 78 such as shown in Figs. 8 to 11 inclusive. This device 78 may be placed upon or secured to a suitable table 79 and comprises a base plate 81 having a front guide edge 82 from which a positioning member 83 projects. Adjacent the rearward edge of the plate 78 a pair of brackets 84 and 85 are secured in upwardly projecting relation by means of screws 86. In the lower parts of the brackets 84 and 85 are horizontal pins 87 on the inner ends of which levers 88 are pivotally mounted in forwardly extended position, such levers having bodies 89 on the forward ends thereof to which guide plates 91 are secured in spaced relation and parallel to the front guide edge 82. As best shown in Fig. 11, a compression spring 92 is placed under the rearward end 94 of each lever 88, the purpose of these springs 92 being to rotate the levers in such direction that the guides 91 will be urged downwardly toward the top of the table 79. As indicated at 95 in Fig. 11, cam means are provided for lifting the levers 88 into positions such as indicated by dotted lines 96, thereby raising the guides 91. Such cam means 95 are formed on a rod or bar 95a which is extended through openings 97 and 98 in the for-

ward portions of the brackets 84 and 85, one end of such bar 95a being bent at right angles to form a handle 101 whereby the bar 95a may be rotated so as to cause the cams 95 to lift the levers 88.

Aligned openings 104 and 105 are provided in the upper parts of the brackets 84 and 85 to support a horizontal bar or shaft 106 having a collar 107 on one end thereof and an operating knob 108 on its other end. The shaft 106 has an unthreaded portion 109 and a threaded portion 110, and on the shaft are mounted levers 111 and 112, the lever 111 having a hub portion 113 engaging the unthreaded section 109 of the shaft 106, and the lever 112 having a hub portion 114 which is threaded upon the threaded portion 110 of the shaft 106. The lever 111 does not move axially relative to the shaft 106, but may rotate through a relatively small arc so that a joint guide 116, which projects forwardly from the lever 111, may be raised and lowered relative to the surface of the table 79 as indicated in Fig. 10. The lever 112, being threaded on the portion 110 of the shaft 106, is moved axially in response to rotation of the shaft 106 and may be swung on the axis of the shaft 106 through a short arc so as to raise and lower a joint guide bar 117 which projects forwardly from the lever member 112.

As best shown in Fig. 10, the forward end of each lever 111 and 112 has an opening 118 therein 30 adapted to receive a pin or bar 119 projecting rearwardly from the cooperating bar 116 or 117. In the forward ends of the levers 111 and 112, screws 121 are provided for making clamping engagement with the pins 119. Each lever 111 and 35 112 has a portion 122 projecting downwardly from the hub thereof, such as the hub 114 of the lever 112. In each of these portions 122 is a vertical notch 123, and each notch 123 is adapted to be engaged by an eccentric 124 formed on a bar 40 125 carried by a pair of small brackets 126 which are secured by means of screws 127 between the brackets 84 and 85 and beneath the shaft 106. The bar 125 is provided with a handle 128 whereby it may be rotated so as to cause rotation of the eccentric portion 124 of the bar, this eccentric portion lying in the notches 123 of the levers 111 and 112, causing such levers to rotate in anti-clockwise direction, as shown in Fig. 10, whereby to raise the levers and the bars 116 and 117 which 50 project therefrom, as indicated by dotted lines 130 in Fig. 10. It will be noted that the positioning member 83 is aligned with the inner edge or face 132 of the bar 116, and the width of the bar 116 is the same as the joint dimension J of 55 Fig. 7. Bars 116 and 117 of other dimensions may be employed for joints of different widths.

The cover sheet 31 shown in Fig. 3 has glue applied to the inner or rear face thereof, and with the members 91, 116, and 117 in raised position, the cover sheet 31 is moved under these members 91, 116, and 117 to bring the front guide edge 41 into engagement with the front guide shoulder 82 of the body 81, with the member 83 engaging the notch 40 so that the inner face 132 of the bar 116 will lie above the back reference line X—X. The handle 101 is then rotated so as to lower the levers 88, thereby dropping the members 91 into engagement with the cover sheet, holding the same in position on the table 79. The book body 20 is then referred to for the proper width b of the back liner 34 to be employed, and the back liner of such proper width b is selected from a supply of back liners. Then, by rotation of the shaft 106, the 75

screw 110 is caused to move the member 112 so as to bring the bar 117 into such position that the space between the inner face 132 of the bar 116 and the face 135 of the bar 117 will correspond to the dimension b . To facilitate adjustment of the bars 116 and 117 into properly spaced position in accordance with the back dimension of the book body to be covered, the lever members 111 and 112 are provided with upwardly projecting lugs 136 having inner faces 137 and 138 lying in the same planes as the faces 132 and 135 of the bars 116 and 117. The selected back liner 34 is placed with its width dimension between the shoulders or faces 137 and 138, and the screw 110 is rotated until these shoulders are spaced apart a distance corresponding to the width dimension b .

After the setting of the bars 116 and 117 as described in the preceding paragraph, the handle 128 is rotated so as to drop the bars 116 and 117 into engagement with the surface of the cover sheet which is in place upon the table 79. The members 89, 116, and 117 now define the proper positions for the liner members 32, 33, and 34, 25 the liner member 34 being placed between the faces 132 and 135 of the bars 116 and 117, after which the liner member or board 32 is placed so that it will engage the front face of the leftward member 91 and the outer face 141 of the bar 116. 30 In a corresponding manner, the liner member or board 33 is placed so as to engage the front face of the rightward member 91 and the rightward face 142 of the bar 117. The levers 101 and 128 are then rotated so as to lift the members 91, 35 116, and 117 to permit removal of the cover sheet 31 which now has the liner members 32, 33, and 34 adhering to the rear face thereof, this partly completed book cover now being ready for the turning in of the fold-in edges 35, 36, 37, and 38, 40 after which the cover may be placed upon the book body 20 in the customary manner.

In another practice of my invention, cover sheets of various standard sizes may be decorated, but not printed with book titles, and held in stock ready for use as needed. I have accordingly in Fig. 4 shown a cover sheet 31a having merely the vari-colored decoration 71 thereon, and other means of decoration such as a panel 71a. This cover sheet 31a now has suitable decoration thereon and is also provided with an indication, such as a notch 40, defining the back reference line $X-X$. When a book body requiring this particular size of cover is brought in for recovering, the suitable lettering is first printed on the front 45 of the cover sheet 31a, in spaced relation to the guide edges 41 and 42 of the cover sheet, at dimensions determined by reference to the dimensions of the book body to be recovered, in accordance with the general procedure hereinbefore set forth. 50 The rear face of the cover sheet 31a is then given a coat of glue, and by use of the device 78 shown in Fig. 8 the liner members are affixed in proper aligned relation to the glued rear face of the cover sheet 31a.

It will be understood that the reference line $X-X$ may have positions other than as shown in Fig. 7 coinciding with the inner edge of a joint. For example, as shown in Fig. 12, the reference line $X'-X'$ may be at a distance R' from the side guide edge 42 of a cover sheet 31b, such distance R' being determined with reference to the dimensions of the book body to be covered so that it will pass through the center of the back liner 34a instead of along one edge of the back liner as disclosed in Fig. 7.

Where this practice of the invention is followed, an aligning device 78a may be used in the manner shown in Fig. 12, this device 78a being the same as the device 78 shown in Fig. 8, with the exception that the shaft 106a thereof, which corresponds to the shaft 106 of Fig. 8, has a right-hand threaded portion 140 and a left-hand threaded portion 141 respectively engaging the hubs of the lever members 112 and 111 so that the joint defining bars 117 and 116 will move together and apart on opposite sides of a locating projection 83a adapted to engage a notch 40a in the edge 41 of the cover sheet 31b. The liner members 32a, 33a, and 34a will be positioned in definite predetermined relation to the front guide edge 41 and the side guide edge 42 of the cover sheet 31b, owing to the fact that the members 91 of the device 78a are spaced a distance L from the edge 82 of the plate 81, and that the notch 40a establishes the reference line $X'-X'$ at a predetermined distance R' from the edge 42. Any deviation of the cover sheet 31b from an intended size thereof, as indicated by dotted lines 150 and 151, will be compensated for without interfering with the proper marking of the cover sheet or the proper placing of the liner members. Likewise, small deviations in the dimensions of the liner members 32a and 33a, as indicated by dotted lines 153 and 154, will be in the edges of such liner members remote from the guides 91, 116, and 117 so that the proper positioning and alignment of the liner members, or their alignment, may be obtained with accuracy and ease.

I claim as my invention:

1. A device for positioning liner members on a cover sheet having a notch in substantially the center of the head guide edge thereof, including: a support having a face to receive a cover sheet; guide means for positioning said cover sheet with its inner face exposed, said guide means having a head guide and a positioning member for engaging said notch when said cover sheet is in engagement with said head guide; and liner guide means mounted on said support, said liner guide means including a head liner guide operative in spaced relation to said head guide, and joint defining guides comprising a pair of members extending perpendicularly to said head guide and being adapted to receive a back liner therebetween, there being means for adjusting said members relatively together and apart while maintaining the same equidistant from said positioning member.

2. A device for positioning liner members on a cover sheet having a notch in substantially the center of the head guide edge thereof, including: a support having a face to receive a cover sheet; guide means for positioning said cover sheet with its inner face exposed, said guide means having a head guide and a positioning member for engaging said notch when said cover sheet is in engagement with said head guide; liner guide means mounted on said support, said liner guide means including a head liner guide operative in spaced relation to said head guide, and joint defining guides comprising a pair of members extending perpendicularly to said head guide and being adapted to receive a back liner therebetween, there being means for adjusting said members relatively together and apart while maintaining the same equidistant from said positioning member; and means for raising and lowering said liner guide means relative to said face of said cover support.

3. A book-cover making apparatus of the class 75

described for employment with a cover sheet having lettering on its outer face and a reference mark visible on its inner face at a predetermined position relative to the lettering, said apparatus including: a bed plate to receive said cover sheet; guide means to abut and align one edge of the cover sheet on the bed plate; a position indicator for registration with said reference mark to fix the position of the sheet along said guide means; a second guide means positioned to overhang the cover sheet and to abut edges of cover boards thereon; a pair of parallel guide arms positioned to extend centrally over said cover sheet and to abut edges of said cover boards thereon; and manual adjustment means operatively connected with said arms to simultaneously shift said arms towards or away from each other.

4. A book-cover making apparatus of the class described for employment with a cover sheet having central lettering on its outer face and a central marginal reference mark, said apparatus including: a bed plate to receive said cover sheet; a guide means on said bed plate to abut and align one edge of the cover sheet; a position indicator for registration with said reference mark to fix the position of the sheet along said guide means; a second guide means positioned to overhang the cover sheet and to abut edges of cover boards thereon; a pair of parallel guide arms, one on each side of said position indicator, said arms being disposed to abut other edges of said cover boards to fix the positions of said boards along said second guide means; and manually operable control means for said arms adapted to shift the arms simultaneously towards or away from said position indicator.

5. A book-cover making apparatus of the class described for employment with a cover sheet having lettering on its outer face and a reference mark visible on its inner face at a predetermined position relative to the lettering, said apparatus including: a bed plate to receive said cover sheet; guide means to abut and align one edge of the cover sheet on the bed plate; a position indicator for registration with said reference mark to fix the position of the sheet along said guide means; a second guide means positioned to overhang the cover sheet and to abut edges of cover boards thereon, said second guide means being movable towards and away from the bed plate to clamp said cover sheet thereagainst; a control member operatively connected with said second guide means; a pair of parallel guide arms positioned to extend centrally over said cover sheet and to abut edges of said cover boards thereon, said guide arms being movable towards and away from said bed plate and adjustable towards and away from each other; means to control the movement of said pair of arms towards and away from the bed plate; and manually operable adjustment means to move said arms simultaneously towards or away from each other.

6. A book-cover making apparatus of the class described for employment with a cover sheet having lettering on its outer face and a notch in one edge at a predetermined position relative to the lettering, said apparatus including: a bed plate to receive said cover sheet; guide means to abut and align said notched edge of the cover sheet on the bed plate; a position indicator on the bed plate for registration with said notch to fix the position of the sheet along said guide means; a

second guide means positioned to overhang the cover sheet and to abut edges of said cover boards thereon; a pair of parallel guide arms positioned to extend centrally over said cover sheet and to abut edges of said cover boards thereon; and manual adjustment means operatively connected with said arms to simultaneously shift said arms towards or away from each other.

7. A book-cover making apparatus of the class described for employment with a cover sheet having central lettering on its outer face and a notch in one edge in a central position relative to said lettering, said apparatus including: a bed plate to receive said cover sheet; a guide means on said bed plate to abut and align said notched edge of the cover sheet; a position indicator on the bed plate for registration with said notch to fix the position of the sheet along said guide means; a second guide means positioned to overhang the cover sheet and to abut edges of cover boards thereon; a pair of parallel guide arms, one on each side of said position indicator, said arms being disposed to abut other edges of said cover boards to fix the positions of said boards along said second guide means; and manually operable control means for said arms adapted to shift the arms simultaneously towards or away from said position indicator.

8. A device for positioning liner members on a cover sheet for a book cover, said cover sheet having a reference cut formed therein, said positioning device including: guide means for positioning said cover sheet with its inner face exposed, said guide means having a head guide to abut one edge of said cover sheet and a projection for engagement in said reference cut to determine the correct position of said cover sheet along said head guide, liner guide members adjustably supported; and means operative to bring said guide members into cooperative relation to the positioned cover sheet, so as to define on the inner face thereof positions for said liner members.

9. A device for positioning liner members on a cover sheet for a book cover, said cover sheet having a reference notch cut therein, said positioning device including: guide means for positioning said cover sheet with its inner face exposed, said guide means having a head guide to abut one edge of said cover sheet and a projection for engagement in said reference notch to determine the correct position of said cover sheet along said head guide; liner guide means adjustably supported, and means operative to bring said guide members into cooperative relation to the positioned cover sheet, so as to define on the inner face thereof positions for said liner members.

10. A device for positioning liner members on a cover sheet for a book cover, said cover sheet having a reference recess formed therein, said positioning device comprising: a head guide to engage one edge of said cover sheet; a projection operatively arranged relatively to said head guide so that it extends into said reference recess, whereby said sheet may be positively positioned relatively to said head guide and constrained against parallel movement in either direction relative to said head guide; and liner guide means mounted on the positioning device for locating the position of liner members on said cover sheet.
